FUSE SOCKET

Jay C. Cowing, Cleveland, Ohio

Application July 9, 1938, Serial No. 218,458

6 Claims. (Cl. 200—133)

My invention relates in general to fuse sockets and more particularly to fuse sockets adjustably arranged for electrical connections between terminals spaced at various distances apart.

5 In the wiring systems for buildings which were constructed several years ago, the circuits were designed to be protected against overloads by the use of fuse wires connected between spaced terminals.

10 An object of my invention is to eliminate the fuse wires in these circuits and to substitute therefor a threadable fuse socket which is adapted to receive a fuse provided in a threaded plug. In mounting a threadable fuse socket in association with the spaced terminals of an old wiring system, a great deal of difficulty is encountered in making the threadable fuse socket universal in order to fit the spaced terminals having various distances between same.

20 Another object of my invention is to eliminate this difficulty by providing a threadable fuse socket having adjustable arranged electrical connections for accommodating terminals spaced at various distances apart. While my invention finds particular application to the modernization 25 of the wiring systems, it is particularly to be pointed out that my invention finds utility in association with any wiring system to protect the circuits against overload.

30 Another object of my invention is the provision of swingable connecting links which may be adjustably set to accommodate terminals spaced at various distances apart in which the adjustments are made by means of the screws that make electrical connections with the threadable fuse plug.

Another object of my invention is the provision of a simple and reliable construction which may be manufactured with a minimum number of parts.

40 Another object of my invention is to employ the screws which make electrical connections with the threaded fuse plug for the additional purpose of adjustably setting the position of the swingable connecting links which are connected 45 to the terminals of the wiring circuit.

Other objects and a fuller understanding of my invention may be had by referring to the following description and claims, taken in conjunction with the accompanying drawing, in which:

Figure 1 illustrates a fragmentary portion of a panel board having an electrical circuit in which my fuse socket may be mounted;

55 Figure 2 is a cross-sectional and enlarged view

of my fuse socket, taken along the line 2—2 of Figure 1; and

Figure 3 is a view looking upwardly from underneath my fuse socket.

A wiring system for buildings may comprise a panel board having a plurality of circuits and switches connected to a plurality of bus bars to give sectionalized control over the various branches of the electrical circuit. In Figure 1 of the drawing, I have illustrated a fragmentary portion of a panel board illustrating a switch 10 which may be electrically connected to bus bars 11 and 12. Electrically associated with one side of the switch 10 is a pair of spaced terminals 13 and 14, and electrically associated with the other side of the switch is a pair of spaced terminals 15 and 16. The switch 10, the bus bars 11 and 12, and the terminals may be suitably mounted on a panel board indicated by the reference character 17. In the wiring system for buildings which were constructed several years ago, the circuits, such for example, as the one illustrated in Figure 1, were designed to be protected against overload by the use of a fuse wire connected respectively between the terminals 13 and 14 and the terminals 15 and 16. In accordance with an object of my invention I eliminate the employment of the fuse wires and substitute therefor a threadable fuse socket indicated generally by the reference character 20.

In the interest of simplicity and economy of manufacture, my threadable fuse socket 20 comprises generally an insulated housing 21 having a recess 22 into which is positioned a threadable fuse receptacle 23 adapted to receive a threadable fuse plug such as now may be purchased on the market. The bottom of the threadable fuse receptacle 23 is provided with a laterally disposed flange 24 which is arranged to engage the bottom of the recess. The laterally disposed flange 24 is provided with two openings 25 and 26 which receive respectively the screws 32 and 33. As illustrated in Figure 2, the head of the screw 32 is arranged to make electrical contact with the fuse receptacle 23 and holds the same in a secured position within the recess 22. The head of the screw 33 is arranged to be electrically insulated from the threadable fuse receptacle 23. To this end, the opening 26 in the laterally disposed flange 24 is enlarged to receive a raised shoulder 27 against which the head of the screw 33 engages. By means of this construction, the head of the screw 33 constitutes a terminal which is designed to be electrically connected to one side of a threadable fuse plug fitting in the

threadable fuse receptacle 23, which receptacle constitutes the other side of the circuit for the connection with the threadable fuse plug.

The screws 32 and 33 fit into openings 28 and 29 provided in the base of the insulated housing 21 and their lower ends threadably engage threaded openings 36 and 37 provided in the respective ends of a pair of swingable connecting links 34 and 35. The adjacent ends of the swingable connecting links 34 and 35 are electrically separated by means of a ridge portion 31 integrally formed with the bottom of the insulated housing 21. The insulated rib 31 may be of any particular shape in order to enable the swingable connecting links 34 and 35 to swing about the screws 32 and 33 and may comprise an enlarged portion 30 as indicated in Figure 3 which constitutes a support for the insulated housing 21 when the insulated housing 21 is mounted directly against a panel board. The outer ends of the swingable connecting links 34 and 35 may be provided respectively with slotted openings 38 and 39 to provide further accommodation for fitting terminals of various distances between the same.

In mounting my fuse socket between spaced terminals, such for example, as the terminals 13 and 14, in Figure 1, the two screws 32 and 33 are slightly loosened to permit the swingable connecting links 34 and 35 to be rotated about the screws 32 and 33 until the slotted opening 38 and 39 register with the threaded openings provided in the terminals 13 and 14, after which the screws 40 and 41 may be inserted through the slotted openings 38 and 39 and threadably engage the terminals 13 and 14. After the position of the swingable connecting links 34 and 35 is determined, the two screws 32 and 33 may then be tightened to provide a good electrical and mechanical connection. Inasmuch as the connecting links may be rotated about the screws 32 and 33, my fuse socket becomes substantially universally adaptable to terminals of various distances between the same. To protect the circuit against overload, the threadable fuse socket need be only connected to one side of the line and the other side of the line may be connected, such for example, between the terminals 15 and 16 by a wire 44 under the screws 42 and 43, which wire is substituted in place of a fuse wire. While I have described my invention as being particularly adaptable to modernizing electrical circuits of buildings which were constructed several years ago, it is manifest that my invention finds particular utility in connection with electrical circuits of all kinds requiring fuses for protecting the circuits against overload.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. A fuse socket adjustably arranged for electrical connection between terminals of various distances between same comprising, in combination, an insulated housing having a recess, said insulated housing having two spaced openings extending from the bottom of the recess to the bottom of the housing, a fuse receptacle mounted in the recess, the bottom of said receptacle having a laterally disposed flange portion arranged to engage a side portion of the bottom of the

recess, said flange portion having an opening registering with one of said spaced openings, an electrical connecting link swingably positioned beneath the insulated housing, said connecting link having a threadable opening provided in one of its ends and positioned in alignment with one of said spaced openings, a second electrical connecting link swingably positioned beneath the insulated housing, said second connecting link having a threadable opening provided in one of its ends and positioned in alignment with the other of said spaced openings, a screw extending through the opening in the flange portion and the registering spaced opening and threadably engaging the threadable opening of said first mentioned connecting link, said screw electrically connecting the fuse receptacle and the first mentioned connecting link together and also securing same to the insulated housing, a second screw extending through the other said spaced opening and threadably engaging the threadable opening in the said second connecting link and securing same to the insulated housing, said second screw having a head constituting terminal means within the said recess, said connecting links being swingable about the said screws and accommodating terminals of various distances between same.

2. A fuse socket adjustably arranged for electrical connection between terminals of various distances between same, comprising, in combination, an insulated housing having a recess, said insulated housing having two spaced openings extending from the bottom of the recess to the bottom of the housing, a fuse receptacle mounted in the recess, the bottom of said receptacle having a laterally disposed flange portion arranged to engage a side portion of the bottom of the recess, said flange portion having an opening registering with one of said spaced openings, an electrical connecting link swingably positioned beneath the insulated housing, said connecting link having a threadable opening provided in one of its ends and positioned in alignment with one of said spaced openings, a second electrical connecting link swingably positioned beneath the insulated housing, said second connecting link having a threadable opening provided in one of its ends and positioned in alignment with the other of said spaced openings, a screw extending through the opening in the flange portion and the registering spaced opening and threadably engaging the threadable opening of said first mentioned connecting link, said screw electrically connecting the fuse receptacle and the first mentioned connecting link together and also securing same to the insulated housing, a second screw extending through the other said spaced opening and threadably engaging the threadable opening in the said second connecting link and securing same to the insulated housing, said second screw having a head constituting terminal means within the said recess, said connecting links being swingable about the said screws and accommodating terminals of various distances between same, said housing having a rib portion extending between the adjacent ends of the connecting links.

3. A fuse socket adjustably arranged for electrical connection between terminals of various distances between same, comprising, in combination, an insulated housing having a recess, said insulated housing having two spaced openings extending from the bottom of the recess to the bottom of the housing, a fuse receptacle mounted in the recess, the bottom of said receptacle hav-

ing a laterally disposed flange portion arranged to engage a side portion of the bottom of the recess, said flange portion having an opening registering with one of said spaced openings, an electrical connecting link swingably positioned beneath the insulated housing, said connecting link having an opening provided in one of its ends and positioned in alignment with one of said spaced openings, a second electrical connecting link swingably positioned beneath the insulated housing, said second connecting link having an opening provided in one of its ends and positioned in alignment with the other of said spaced openings, engaging means extending through the opening in the flange portion and the registering spaced opening and engaging the opening of said first mentioned connecting link, said engaging means electrically connecting the fuse receptacle and the first mentioned connecting link together and also securing same to the insulated housing, second engaging means extending through the other said spaced opening and engaging the opening in the said second connecting link and securing same to the insulated housing, said second engaging means having a portion constituting terminal means within the said recess, said connecting links being swingable about the said engaging means and accommodating terminals of various distances between same.

4. A fuse socket adjustably arranged for electrical connection between terminals of various distances between same, comprising, in combination, an insulated housing having a recess, said insulated housing having two spaced openings extending from the bottom of the recess to the bottom of the housing, a fuse receptacle mounted in the recess, the bottom of said receptacle having a laterally disposed flange portion arranged to engage a side portion of the bottom of the recess, said flange portion having an opening registering with one of said spaced openings, an electrical connecting link swingably positioned beneath the insulated housing, said connecting link having an opening provided in one of its ends and positioned in alignment with one of said spaced openings, a second electrical connecting link swingably positioned beneath the insulated housing, said second connecting link having an opening provided in one of its ends and positioned in alignment with the other of said spaced openings, engaging means extending through the opening in the said portion of the receptacle and the registering spaced opening and engaging the opening of said first mentioned connecting link, said engaging means electrically connecting the receptacle and the first mentioned connecting link together and also securing same to the insulated housing, second engaging means extending through the other said spaced opening and engaging the opening in the said second connecting link and securing same to the insulated housing, said second engaging means having a portion constituting terminal means within the said recess, said connecting links being swingable about the said engaging means and accommodating terminals of various distances between same.

6. An electrical socket adjustably arranged for electrical connection between terminals of various distances between same, comprising, in combination, an insulated housing having a recess, said insulated housing having two spaced openings extending from the inside of the recess to the outside of the housing, a receptacle mounted in the recess, said receptacle having a portion with an opening registering with one of said spaced openings, an electrical connecting link swingably positioned outside the insulated housing, said connecting link having an opening provided in one of its ends and positioned in alignment with one of said spaced openings, a second electrical connecting link swingably positioned outside of the insulated housing, said second connecting link having an opening provided in one of its ends and positioned in alignment with the other of said spaced opening, engaging means extending through the opening in the said portion of the receptacle and the registering spaced opening and engaging the opening of said first mentioned connecting link, said engaging means electrically connecting the receptacle and the first mentioned connecting link together and also securing same to the insulated housing, second engaging means extending through the other said spaced opening and engaging the opening in the said second connecting link and securing same to the insulated housing, said second engaging means having a portion constituting terminal means within the said recess, said connecting links being swingable about the said engaging means and accommodating terminals of various distances between same.

5. An electrical socket adjustably arranged for
